HENRY J. SAUER, OF FAIRFIELD, CONNECTICUT, ASSIGNOR TO THE KILBORN-SAUER COMPANY, OF FAIRFIELD, CONNECTICUT, A CORPORATION OF CONNECTICUT

REFLECTOR SIGNAL

Application filed December 2, 1929. Serial No. 410,998.

My invention relates to an improved reflector construction, the object being to provide a simple, inexpensive, easily assembled and yet strong and durable construction.

5 In the accompanying drawings—

Fig. 1 is a side elevation, partly in section, on the line 1—1 of Fig. 2 of my improved reflector;

10 Fig. 2 is a front elevation thereof partly broken away.

The casing of the reflector is formed of two substantially flat sections 1—2 with telescopic edges. The edges of each of these sections 1—2 are also scalloped to form in effect a 15 deeply corrugated portion on each section extending entirely around the reflector casing when the sections are assembled, thereby stiffening and assisting in preventing collapse of the same, and further preventing 20 one section from shifting on the other. In the section 2, I provide a plurality of reflector elements 3—3. At the back of each of these elements is an enlarged portion 3^a. These reflector elements stand in openings in 25 the section 2 which are preferably symmetrically disposed therein. The size of each of these openings is sufficient to permit the front of its reflector element to pass through, the enlarged portion 3^a of the element being too 30 large to pass through and therefore remaining in the inside of the housing formed by the sections 1—2 when assembled. Within the housing, I provide suitable means to hold each of these reflector elements snugly in 35 place against rattling. One suitable means may comprise one or more soft pad pieces indicated at 4, which practically fill the space in the housing and exclude dust. These pad pieces may be of thick felt or the like and 40 therefore act as a cushion to absorb shock, tending to prevent breakage should one or more units be struck. 5 is a bracket of any suitable construction, the same being in the form of a strap as shown in the drawings.

45 This bracket is secured to the back section 1 of the housing by devices which perform a double function. Each of these devices comprises a body portion 6 which has a stud extension 7 at the rear and a screw threaded 50 bore at the front. Each body 6 performs the

function of a spacer between the sections 1 and 2 to hold them against central collapse. Holes are provided in the rear section 1 to permit the stud portions 7 to go through and engage the bracket 5 in any desired way 55 as by upsetting the ends of the studs. 8—8 are screws which go through holes in the front section 2 and screw into the spacer bodies 6—6. When the several parts are secured together, all rattling or looseness 60 caused by vibration is prevented. Should there be occasion to replace one or more of the reflector elements, the screws 8—8 may be removed and the outer section 2 may be withdrawn from the section 1. 65

What I claim is:

A reflector, comprising a housing formed of two substantially flat sections with offset telescopic flanges at the edges thereof, said flanges being corrugated to strengthen 70 said sections and also to prevent one section from turning on the other, one of said sections having a plurality of openings therein, glass reflector elements in said openings, the front end of each of said elements being hemispherical and the rear end of each of said elements having an integral glass flange thereon, the flanges on said elements being held between said sections, and means for clamping 75 said sections together. 80
